UNITED STATES PATENT OFFICE.

JOHN W. BABB, OF CHICAGO, ILLINOIS.

METHOD OF CUTTING GARMENTS.

1,274,364.

Specification of Letters Patent.

Patented Aug. 6, 1918.

Application filed April 1, 1918. Serial No. 225,876.

To all whom it may concern:

Be it known that I, JOHN W. BABB, a citizen of Canada, residing at Chicago, county of Cook, State of Illinois, have invented a certain new and useful Method of Cutting Garments, of which the following is a specification.

My invention relates to suits of the kind worn by business men and others, commonly known as sack suits, and manufactured from woolen and other materials. It has been the practice heretofore in making suits of this kind to use a certain length of cloth for the coat, vest and trousers of a suit. One object of the present invention is to obtain from this same length of cloth a suit and an extra pair of trousers, thereby economizing material. This is accomplished within the limits of certain sizes by slightly modifying the usual pattern parts in certain particulars and placing the same upon the length of cloth in a particular order. In general the modification of the usual patterns consists in slightly shifting certain seams in the coat and trousers and in replacing the usual vest fronts by fronts composed of two sections each. The novel arrangement of the pattern parts upon the cloth is best shown by the drawing.

For a fuller understanding of the invention reference should be had not only to said drawing but also to the following detailed description. The scope of the invention is set forth in the appended claims.

In said drawing Figure 1 is a diagram illustrating a usual pattern length of doubled cloth with one arrangement of patterns thereon, the whole illustrating prior art practice; Fig. 2 illustrates a vest front pattern of prior art design, showing particularly a common way of cutting V's therein; Fig. 3 illustrates a vest front cut into two sections by cutting in the general direction of the V's of Fig. 2 to the point of intersection; Fig. 4 illustrates a vest back; Fig. 5 is a diagram illustrating the same pattern length of doubled cloth as in Fig. 1, but with patterns thereon designed and positioned in accordance with the present invention. Throughout these views like characters refer to like parts.

Referring to said drawing in detail, 10 designates the pattern of cloth out of which the suit is to be cut, whether by the prior art method of Fig. 1, or in accordance with the present invention, as depicted in Fig. 5. The length of the pattern in the drawing

may be assumed to be three and one third (3 $\frac{1}{3}$) yards and its width twenty-eight and three fourths (28 $\frac{3}{4}$) inches. In Figs. 1 and 5 the cloth is represented folded lengthwise so as to lie double beneath the patterns. Out of such a piece, a suit may be cut for a man five feet seven inches (5 ft. 7 in.) high and thirty-seven inch (37 in.) breast measure. 65 If the suit be cut according to prior art methods the pattern parts may be cut and arranged as shown in Fig. 1; if cut and arranged according to the present invention then the pattern parts would be cut and arranged as shown in Fig. 5 and thus an extra pair of trousers gotten out of the same length and width of cloth. In the drawing the selvage edge is indicated by the dotted line 11. 70

Now in order to bring about the pattern design and arrangement of Fig. 5, I modify the pattern parts of Fig. 1 slightly and then arrange them on the cloth as shown in Fig. 5. Thus the coat front 12 of Fig. 1 has its 80 shoulder seam edge cut off along the dotted line 13. This change produces the new front 12' of Fig. 5. The coat back 14 of Fig. 1 is enlarged along its shoulder seam edge by cutting along the dotted lines 15. This 85 change produces the new coat back 14'. Thus what is cut off the front is added to the back. This has the effect of bringing the shoulder seam slightly forward, in the case assumed not more than three eighths 90 (3 $\frac{1}{8}$) of an inch. 75

Similarly the old trousers front 16 is diminished by cutting off the inside seam edge near the crotch along the dotted line 17 and its waist line dimension increased by cutting the side seam edge near the waist line along the dotted lines 18. These changes in the trousers front 16 produce the new trousers fronts 16' and 16''. In each of these patterns the lines 20 and 21 are to be followed, one for the left leg and the other for the right leg of each pair, as usual. The trousers back 22 of Fig. 1 has its side seam edge cut off along the dotted line 23. The adjacent V is also preferably narrowed by 105 cutting along the dotted line 24 but this latter is not necessary and may be omitted, the line 23 being varied in position accordingly, so as to give the correct waist measure. The inside seam edge near the crotch 110 is also extended by cutting along the dotted lines 25. These changes in the trousers backs produce the new backs 22' and 22'' of Fig. 5, except that it is necessary in order to ob-

- tain the layout of Fig. 5 to cut the back 22' along the line 26 so as to accommodate the other parts. To provide the necessary material at this point the triangular piece 27 is 5 cut out of the cloth at another point and added to the back 22'. This brings extra pieces together in the crotch of one pair of trousers but leaves the other pair without extra pieces. This is the only place at which 10 an extra piece is added to the old pattern parts to provide the new. In these changes of the trousers fronts and backs the side seam of each pair is brought slightly backward, not more than one half ($\frac{1}{2}$) an inch 15 in the case assumed, the crotch seam is also brought slightly forward, not more than five eighths ($\frac{5}{8}$) of an inch in the case assumed, and one pair has crotch pieces added.
- The upper sleeve pattern 28 of Fig. 1 is 20 diminished in width near the top and bottom by cutting along the dotted lines 29 and 30. This change produces the new upper sleeve pattern 28'. To compensate for the diminishing of the upper sleeve pattern, 25 the lower sleeve pattern 31 is increased in width at its top and bottom by cutting along the dotted lines 32 and 33. This change produces the new under sleeve 31'. These changes in the upper and under sleeve patterns shift the rear or back seam slightly forward at the top and bottom. In the case assumed the shift at the top is not more than one half ($\frac{1}{2}$) an inch and that at the bottom about three fourths ($\frac{3}{4}$) of an inch.
- 35 The vest back 34, shown in Fig. 4, is cut out of other cloth than the parts shown in Figs. 1 and 5. When cut in the form shown in full lines in Fig. 4 the vest back is ready for use with the vest parts of Fig. 5.
- 40 The vest front 36 of Fig. 1 of the prior art design is to be replaced by two vest front sections 36' and 36''. These sections are shaped as shown in Fig. 5. Their configuration is determined by taking the prior 45 art vest front 36, cutting it into two sections by cutting generally in the direction of the dotted lines 37 and 38 (Fig. 2) and thus producing the two sections shown in full lines in Fig. 3.
- 50 The line of cut between these sections may be varied considerably but those illustrated in Fig. 3 illustrate the principle. By adding to these sections as indicated by the dotted lines 39 and 40, the outline for cutting the front sections 36' and 36'' is provided. In some instances it may be necessary or desirable to shift the shoulder seam of the vest in the same way the shoulder seam of the coat is shifted. But in the size chosen 55 for illustration, this is not necessary. Where the shoulder seam is thus shifted, as in certain larger sizes, the back 34 is extended by cutting the cloth along the dotted lines 35 and the front section is diminished by 60 cutting along the dotted line 41. In any
- case this shifting of the shoulder seam is usually not greater than a half inch. If the user needs the cloth then he can shift the seam. The coat facing 42 is practically the same in both Figs. 1 and 5. The same is 70 true also of the pocket flap 43 and upper collar 44.
- The coat fronts may be provided with one or more slits or V's 45 according to the shape or fit required to be given the coat. Likewise in the vest, the sections 36' and 36'' can be cut so as to give all the advantages of one or more V's 46 heretofore commonly employed as illustrated on the fronts 36 of Figs. 1 and 2. It will also be noted that 75 the seam formed by sewing the sections 36' and 36'' together will be partially covered by the usual upper vest pocket whose position is indicated in Fig. 2 by the dotted lines 47. In these diagrams the line 48 in 80 the coat front shows the position of the side pocket and the line 49 on the trousers fronts and backs shows the position of the stitching which is commonly employed to give the appearance of a band, no separate band being employed. Likewise the line 50 on the sleeves shows the edge at which the cloth is to be turned up inside the sleeve to give 85 it a finish. Similarly the line 51 at the trousers bottom shows the edge at which the cloth is to be turned back so as to give a slight facing. The lines 52 show the point at which the cloth is to be turned up to 90 form the cuff and the line 53 shows the point to which the top of the cuff comes.
- The arrangement of the modified pattern parts upon the cloth so as to get the extra pair of trousers out of the same cloth is clearly illustrated in Fig. 5. As there 95 shown, the coat back 14' is in one corner of the cloth with its top near the end of the cloth and its rear edge adjacent to one edge of the folded cloth. The coat front 12' is placed next to the coat back 14' and has its lower end near the end of the cloth and 100 its forward edge adjacent to the forward edge of the coat back. The coat facing 42 is positioned so that its lower end lies toward the end of the cloth and its forward edge lies adjacent to the rear edge of the 105 coat front 12'. The top of the facing 42 extends slightly beyond the upper end of the coat front. The trousers fronts 16' and 16'' are arranged bottom to bottom in line 110 with each other and the coat back 14'. They are positioned with their front edges adjacent to the folded edge of the cloth. The upper collar 44 lies between the trousers fronts 16' and 16''. The trousers backs 22' and 22'' are arranged top to top in line with each 115 other and with the coat front 12'. Their front edges lie adjacent to the rear edges of the trousers fronts 16' and 16''. The trousers back 22' which lies nearest to the center of the cloth is cut away at the crotch 120
- 130

- as shown and the triangular piece 27 which is used to fill out this portion of the pattern is located more or less in the arm hole of the coat front 12'. The upper sleeve 31' 5 is positioned with its forward edge adjacent to the selvage edge of the folded cloth and its rear edge adjacent to the rear edges of the trousers backs 22' and 22", being positioned between the crotch points. The vest 10 front section 36' is positioned between the coat facing 42 and the upper sleeve 31'. Its front edge lies adjacent to the rear edge of the trousers back 22'. The under sleeve 28' is located in the corner of the cloth diagonally opposite the coat back 14'. Its rear edge lies adjacent to the rear edge of the trousers back 22". The second vest section 36" lies between the upper sleeve 31' and the under sleeve 28'. The pocket flap 20 43 is located between the upper sleeve 31' and the vest front section 36'.
- It is pointed out that the results attained by the modification of the pattern parts and the arrangement upon the cloth as herein disclosed is not to be had in the case of every set of measurements when the size of the cloth as commonly purchased by the trade is taken into account. The results will be realized, however, within well defined limits. 25 30 The following table indicates the field in which the results described are to be had.

Table.

Breast.	Height.	Yards.	Width cloth.
34	5 ft. 7 in.	3 $\frac{1}{2}$	26 in.
35	"	"	28 $\frac{1}{2}$ "
36	"	"	28 $\frac{1}{2}$ "
37	"	"	28 $\frac{1}{2}$ "
38	5 ft. 8 in.	3 $\frac{1}{2}$	29 "

It will be noted that with the particular layout illustrated in Fig. 5, I have also made provision for considerable variation in fullness of material so as to allow for fitting after the goods have been cut and the parts stitched together for a "try on". Some of these points may be indicated. At the point 56 there is extra material to allow for variation in the fullness of the front of the coat. At the points 57 material is available for letting out the trousers waist more or less as may be required. Again, at the points 58, material is available for addition to the trousers backs to provide increased knee width. Again at point 59, material is available for giving fullness to the vest front. At point 60, there is also extra material available for increasing the width of the coat facing. Where such excess cloth is to be used for fitting in this way, of course the exact lines of the pattern are not followed in cutting but the cut is made so as to include more cloth at the required points. 45 50 55 60 65 Besides allowing for an extra fullness of

the cut at the points indicated above, I also have extra material available at the point 54 adjacent to the lower end of the upper sleeve 28' so that where desired the sleeve may be finished with the short slit which is 70 commonly found at this point, the extra material being used for turning and facing. Similarly extra material at the point 55 along the back edge of the coat back 14' allows the coat to be finished with a slitted 75 tail, the material as before being available for the turn and for facing.

From these considerations it will be seen that I have succeeded in getting a suit and an extra pair of trousers out of the cloth 80 usually required for a suit, within certain limits, by but slightly modifying prior design while arranging the pattern parts upon the cloth in a new way and in a way which will allow for quite a variation in dimensions at those points where such variations are most desirable.

What I claim as new and desire to secure by Letters Patent of the United States is:

1. The method of cutting a business man's 90 suit and an extra pair of trousers from a minimum length of cloth which consists (a) in modifying the pattern parts relative to prior art practice (1) by moving slightly forward the shoulder seams of the coat, the 95 sleeve back seams at the top and bottom, the trousers side seams and the trousers crotch seams, (2) by piecing in the crotch the trousers backs of one pair, and (3) by replacing the prior art vest front by a new vest front 100 made in two sections, and then (b) cutting the material according to the modified pattern parts when laid upon the cloth doubled along a central longitudinal line; as follows: a coat back in one corner of the cloth with 105 its top near the end of the cloth and its rear edge adjacent to one edge of the cloth, a coat front next to said back with its lower end near the end of the cloth and its forward edge adjacent the forward edge of said 110 back, a coat facing with its lower end toward the end of the cloth and its forward edge adjacent to the rear edge of the coat front, the top of said facing extending slightly beyond the upper end of said coat front, a 115 pair of trousers fronts bottom to bottom in line with each other and said coat back with their front edges adjacent to one edge of the cloth, a pair of trousers backs top to top in line with each other and said coat front 120 with their front edges adjacent to the rear edges of said trousers fronts, the trousers back which lies nearest the center of the cloth being cut away at the crotch, a piece for filling out this cut away portion positioned in the 125 space left by the arm hole of said coat front, an upper part with its forward edge adjacent to the edge of the cloth and its rear edge adjacent to the rear edges of said trousers backs between the crotch points, a vest 130

front section between said coat facing and said upper sleeve part with its front edge adjacent to the rear edge of the said adjacent trousers back, an under sleeve part in 5 the corner of the cloth diagonally opposite to said coat back with its rear edge adjacent to the rear edge of the said adjacent trousers back and a second vest front section between said upper and under sleeve 10 parts.

2. The method of cutting a business man's suit and an extra pair of trousers from a minimum length of cloth which consists (a) in modifying the pattern parts relative to prior art practice (1) by moving slightly 15 forward the shoulder seams of the coat and vest, the sleeve back seams at the top and bottom, the trousers side seams and the trousers crotch seams, (2) by piecing in the 20 crotch the trousers backs of one pair, and (3) by replacing the prior art vest front by a new vest front made in two sections, and then (b) cutting the material according to the 25 modified pattern parts when laid upon the cloth doubled along a central longitudinal line, as follows: a coat back in one corner of the cloth with its top near the end of the cloth and its rear edge adjacent to one edge of the cloth, a coat front next to said 30 back with its lower end near the end of the cloth and its forward edge adjacent the forward edge of said back, a coat facing with its lower end toward the end of the cloth and its forward edge adjacent to the rear 35 edge of the coat front, the top of said facing extending slightly beyond the upper end of said coat front, a pair of trousers fronts bottom to bottom in line with each other and said coat back with their front edges 40 adjacent to one edge of the cloth, an upper collar intervening between said bottoms, a pair of trousers backs top to top in line with each other and said coat front with their front edges 45 adjacent to the rear edges of said trousers fronts, the trousers back which lies nearest the center of the cloth being cut away at the crotch, a piece for filling out this cut away portion in the space left by the arm hole of said coat front, an 50 upper sleeve part with its forward edge adjacent to the edge of the cloth and its rear edge adjacent to the rear edges of said trouser backs between the crotch points, a vest front section between said coat facing 55 and said upper sleeve part with its front edge adjacent to the rear edge of the said adjacent trousers back, an under sleeve part in the corner of the cloth diagonally opposite to said coat back with its rear edge 60 adjacent to the rear edge of the said adjacent trousers back, a second vest front section between said upper and under sleeve parts, and a pocket flap located between said upper sleeve part and the first mentioned vest front section.

parts, and a pocket flap located between said upper sleeve part and the first mentioned vest front section.

3. The method of cutting a business man's suit and an extra pair of trousers from a minimum length of cloth which consists (a) in modifying the pattern parts relative to prior art practice (1) by moving slightly 65 forward the shoulder seams of the coat and vest, the sleeve back seams at the top and bottom, the trousers side seams and the trousers crotch seams, (2) by piecing in the 70 crotch the trousers backs of one pair, and (3) by replacing the prior art vest front by a new vest front made in two sections, and then (b) cutting the material according to the 75 modified pattern parts when laid upon the cloth doubled along a central longitudinal line, as follows: a coat back in one corner of the cloth with its top near the end of the cloth and its rear edge adjacent to one edge of the cloth, a coat front next to said back with its lower end near the end of the cloth and its forward edge adjacent to the forward edge of said back, a coat facing with its lower end toward the end of the cloth and its forward edge adjacent to the rear edge of the coat front, the top of 80 said facing extending slightly beyond the upper end of said coat front, a pair of trousers fronts bottom to bottom in line with each other and said coat back with their front edges adjacent to one edge of 85 the cloth, an upper collar part intervening between said bottoms, a pair of trousers backs top to top in line with each other and said coat front with their front edges adjacent to the rear edges of said trousers fronts, the trousers back which lies nearest the center of the cloth being cut away at the crotch, a piece for filling out this cut away portion 90 positioned in the space left by the arm hole of said coat front, an upper sleeve part with 95 its forward edge adjacent to the edge of the cloth and its rear edge adjacent to the rear edges of said trousers backs between the crotch points, a vest front section between 100 said coat facing and said upper sleeve part with its front edge adjacent to the rear edge of the said adjacent trousers back, an under sleeve part in the corner of the cloth diagonally opposite to said coat back with its rear edge adjacent to the rear edge of the 105 said adjacent trousers back, a second vest front section between said upper and under sleeve parts, and a pocket flap located between said upper sleeve part and the first mentioned vest front section.

In testimony whereof I have hereunto subscribed my name this 30th day of March, A. D. 1918.

JOHN W. BABB.
